UNITED STATES PATENT OFFICE

172,016

CLOCK

Gordon W. Florian, Bridgeport, Conn., assignor
to General Time Corporation, New York, N. Y.,
a corporation of Delaware

Application March 24, 1953, Serial No. 24,183

Term of patent 14 years

(Cl. D42—7)

To all whom it may concern:

Be it known that I, Gordon W. Florian, a citizen of the United States, residing at Bridgeport, in the county of Fairfield and State of Connecticut, have invented a new, original, and ornamental Design for a Clock, of which the following is a specification, reference being had to the accompanying drawing, forming a part thereof.

Figure 1 of the drawing is a perspective view of a clock embodying my new design.

Figure 2 is a front elevational view of said clock.

I claim:

The ornamental design for a clock, substantially as shown.
